UNITED STATES PATENT OFFICE

JULIUS KAHN AND HERBERT E. WHITE, OF YOUNGSTOWN, OHIO, ASSIGNEES TO
TRUSCON STEEL COMPANY, OF YOUNGSTOWN, OHIO, A CORPORATION OF MICHIGAN

LATH STRUCTURE

Application filed February 11, 1929. Serial No. 339,087.

The object of the present invention is to provide a novel, simple and effective lath structure, which can be easily applied and which will require a minimum amount of plaster to produce a finished and effective wall.

In the accompanying drawings:

Figure 1 is a view in elevation of a portion of the structure.

10 Figure 2 is a sectional view on the line 2-2 of Figure 1.

Figure 3 is a sectional view on the line 3-3 of Figure 1.

15 Figure 4 is a perspective view showing a section of the lath structure and plaster thereon.

In the embodiment disclosed a backing sheet, designated generally by the reference numeral 5, is employed. It is a multi-ply structure, comprising a rear backing sheet 7 of relatively heavy paper that will act as a supporting body. A facing sheet 8 of lighter

20 paper or similar material, is employed and these two sheets are secured together by an

25 interposed layer or ply 9 of asphaltum or other waterproof material. The backing sheet 5 as thus preferably constructed, is stamped to form continuous longitudinal and transverse reinforcing ribs 10 on its rear

30 side. These ribs produce in the front face correspondingly shaped grooves or channels 11. The surface of the rectangular portions defined by these channels and designated 12 is substantially flat.

35 Over the face is laid a metallic lath structure, preferably consisting of right angularly disposed lath rods 13 and 14 that are welded or otherwise secured together at their

40 points of intersection. These rods are preferably spaced so that certain of the same intersect on the flat surfaces 12 and extend transversely across the channels or grooves 11.

Others extend longitudinally along and over

45 said grooves, being supported by the interposed rods that lie upon the flat surfaces 12.

This metallic fabric is secured to the backing sheet by any suitable means, as staples 15

50 that preferably pass through the flat surfaces 12 and embrace certain of the rods ad-

jacent their points of intersection with the other rods. A very simple and practicable structure is thus produced, in which the backing ply constitutes the support and is insulated from the moisture due to the application of the wet plaster against the face of the backing sheet.

The front lighter sheet provides means for bonding the plaster to the backing sheet.

55 Inasmuch as the metal fabric preferably lies substantially against the sheet the body of

plaster necessary to cover the lathing is relatively thin. At the same time a complete

60 key is provided as the plaster can flow into the channels and thus around those rods which lie longitudinally thereof as well as

65 the portions of the rods which pass across the said channels. Moreover the plaster that

70 thus enters and fills the channel forms intersecting reinforcing ribs that serve as material strengthening agents to the wall structure.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

75 What we claim is:

1. A plaster supporting structure, comprising a backing sheet having a generally flat face and spaced apart continuous pockets opening through said face, lath rods extending along said face of the sheet, certain of said rods being located longitudinally over the pockets between the side walls thereof and spaced from their bottoms, and means securing the rods to the sheet.

80 2. A plaster supporting structure comprising a backing sheet having a generally flat face and spaced apart continuous pockets opening through said face, angularly disposed intersecting lath rods laid along said face of the sheet, certain of said rods being located longitudinally over the pockets between the side walls thereof and spaced from

their bottoms, and means securing the rods to the sheet.

3. A plaster supporting structure comprising a backing sheet having rearwardly outstanding intersecting stiffening ribs forming intersecting grooves that open through the face of the sheet, and a lath fabric overlying the face of the sheet and secured thereto.

10 4. A plaster supporting structure comprising a backing sheet having rearwardly outstanding intersecting stiffening ribs forming intersecting grooves that open through the face of the sheet, and a lath fabric overlying the face of the sheet and comprising intersecting rods secured to the sheet, certain of said rods being disposed longitudinally along the open sides of the grooves.

15 5. A plaster supporting structure comprising a backing sheet of generally flat material having spaced apart angularly disposed intersecting ribs on its rear side forming depressed angularly disposed intersecting grooves opening through its front side, and 20 angularly disposed intersecting lath rods lying on the front face of the backing sheet, certain of said rods extending longitudinally along the open sides of the grooves and certain lying on the substantially flat face of the 25 backing sheet and secured thereto.

30 6. A wall structure including a backing sheet having intersecting channels in its front face, lath rods extending over said channels, and a plaster body over the front 35 face of the backing sheet, said body having the lath rods embedded therein and filling the channels, thereby providing intersecting stiffening ribs for the wall structure.

In testimony whereof, we affix our signatures.

JULIUS KAHN.
HERBERT E. WHITE.
